UNITED STATES PATENT OFFICE.

CARL WICHT AND WILLIAM E. DIPPERT, OF DES MOINES, IOWA.

DESIGN FOR A HASP-PLATE.

SPECIFICATION forming part of Design No. 32,323, dated March 6, 1900.

Application filed January 15, 1900. Serial No. 1,566. Term of patent 14 years.

To all whom it may concern:

Be it known that we, CARL WICHT and WILLIAM E. DIPPERT, citizens of the United States of America, and residents of Des Moines, Polk county, Iowa, have invented a new and useful Design for a Hasp-Plate, of which the following is a specification.

The object of this invention is to provide a new and useful design for a hasp-plate for collar-fasteners and the like; and our invention consists of the design hereinafter set forth, pointed out in our claim, and illustrated by the accompanying drawings, in which—

Figure 1 is a plan of a hasp-plate embodying our invention. Fig. 2 is a cross-section on the indicated line 2 2 of Fig. 1. Fig. 3 is an edge view of the hasp-plate. Fig. 4 is a longitudinal section on the indicated line 4 4 of Fig. 1.

In the design, as shown, the numeral 10

designates a hasp-plate, relatively thin and formed with a U-shaped marginal flange 11 on both sides and around one end thereof. The hasp-plate 10 is formed with transverse slots 12, 13, and 14 within the U-shaped flange 11, which flange is materially thicker than the plate. A tongue 15 is formed on one end of the hasp-plate 10 and projects longitudinally therefrom. The tongue is of less width than the hasp-plate 10 and is bent to form an eye parallel with the slots of the plate. The hasp-plate is curved longitudinally.

We claim as our invention—

The design for a hasp-plate, substantially as herein shown and described.

CARL WICHT.

WILLIAM E. DIPPERT.
